PULSATION DAMPENER

Douglas Ragland, Houston, Tex., assignor, by
mesne assignments, to Standard Oil Develop-
ment Company, Elizabeth, N. J., a corporation
of Delaware

Application October 28, 1946, Serial No. 706,198

3 Claims. (Cl. 138—30)

1

The present invention is directed to a device for dampening or suppressing the pulsations in a liquid stream. The device is particularly adapted to suppressing or dampening the pulsations in the outlet line of a reciprocating pump.

It is well known to the art that the liquid stream in the outlet line of a reciprocating pump has a cyclic variation in pressure. That is to say, during each stroke of the pump the pressure rises as the piston forces the liquid through the outlet port and then diminishes on the return stroke as the cylinder is again filled with liquid from the inlet port. In many installations of reciprocating pumps the pulsations in the outlet line are not particularly disadvantageous; however, in some installations it is desirable that such pulsations in the liquid stream be suppressed or damped. For example, in compounding reciprocating pumps it is necessary or desirable to suppress or dampen the vibration in the fluid stream forced from the outlet port of a reciprocating pump to the inlet port of a second in order to prevent excessive wear or even breakage of the second pump.

It is an object of the present invention to devise a device suitable for installation in the outlet line of a reciprocating pump which will suppress or eliminate periodic pressure changes in the outlet stream of the pump.

It is a further object of the present invention to devise a means which may be arranged in the line connecting the outlet port of a reciprocating pump to the inlet port of another reciprocating pump for dampening or suppressing the periodic vibrations in the liquid being fed from one pump to the other pump.

The device of the present invention may be described briefly as involving a metallic case capable of resisting deformation at the pressure to which it is subjected and serving as an exterior element, an elastic member with edges sealed to the external case thereby forming a fluid-tight cavity between a surface of the flexible member and the inner surface of the external case, means arranged for filling the cavity with a compressible fluid and a means arranged for connecting the device with a stream of liquid having a pulsating pressure whereby the interior of the flexible member is in fluid communication with the pulsating stream.

The construction and advantages of the device of the present invention will be better understood by the following description taken with the drawing in which the sole figure is in the form of an elevation, partly in section, illustrating an embodiment of the present invention.

2

Turning now specifically to the drawing, a cylindrical member or case 11 provided with screw threads 12 and 13 on the exterior end surfaces thereof forms the outer casing of the device. An inner cylindrical member or mandrel 14 is provided with a plurality of perforations 15 in the center portion thereof and one end is provided with external screw threads 16. The screw threads 16 are arranged so that the member may readily be attached to a pipe or line carrying a fluid stream; such a line is not shown in the drawing but it will be understood that it may be a conventional pipe connected, for example, from the outlet of a reciprocating pump to the inlet of another reciprocating pump to allow compounding of the reciprocating pumps.

Mounted between outer case 11 and inner perforated mandrel 14 is a flexible member 17. For convenience this member is hereinafter termed 20 a rubber sleeve, although it will be understood that it may be constructed of any suitable material having the required elasticity and flexibility. A valve 19 is mounted in case 11 to allow the chamber 18 defined between the outer surface of rubber sleeve 17 and the inner surface of case 11 to be filled with a compressible fluid, such as compressed air.

Rubber sleeve 17 has its ends mounted to make a fluid-tight seal with cylinder 11. Means sealing the ends of rubber sleeve 17 include end plates 20 and 21. End plate 20 is in the form of an annulus and has its inner circumference firmly fixed in a fluid-tight manner, as by welding, to mandrel 14. End plate 21 is circular in shape. It will be seen that surfaces of end plates 20 and 21 are adapted to abut the ends of case 11. Cap 22 is attached to case 11 by screw threads and maintains case 11 in contact with end plate 20. End plate 21 is not firmly fixed to mandrel 14 but is retained in position in contact with casing 11 by means of cap 23 which is attached by screw threads to casing 11. Rubber sleeve 17 is of such a configuration that the major portion thereof is in the form of a cylinder with parallel sides while its ends are thickened and tapered to define wedge-shaped surfaces. A support ring 25 is embedded in each end of the sleeve. Each support ring is provided with bolts 25a which provide means for drawing the ends of the sleeve against end plates 20 and 21, respectively.

Secured to end plate 20 by a suitable means, as by welding, is an inner member 26 defining a cylindrical inner surface and a conical outer surface and an outer member 27 having an outer cylindrical surface and an inner conical surface. The tapering surfaces defined by means 26 and

27 cooperate with the wedge-shaped end of rubber sleeve 17 to make a fluid-tight seal when the end of the sleeve is secured to end plate 20 by bolts 25a. The outer surface of member 27 defines a groove having a rubber pack-off ring 28 arranged therein which insures a fluid-tight seal between the outer surface of member 27 and the inner surface of case 11.

Secured to end plate 21 by suitable means, such as welding, are members 29 and 30 having a configuration identical with members 26 and 27, respectively. The outer surface of member 30 defines a groove for receiving a rubber pack-off 28 identical with that described with respect to member 27. When the end of the rubber sleeve 17 is brought into contact with end plate 21 by tightening bolts 25a, a fluid-tight joint is insured.

It is to be noted that the principal difference between end plate 21 and end plate 20 is that end plate 20 is secured to mandrel 14 by suitable means, such as welding, whereas end plate 21 is maintained in fixed position with respect to casting 11 and the member 29 secured to end plate 21 fits slidably on the exterior surface of mandrel 14.

It will be evident that the device of the present invention may be readily assembled and disassembled in construction and repair thereof. When the device is disassembled the most complex unit consists of mandrel 14, end member 20 and tapering members 26 and 27. Rubber sleeve 17 may then be slipped over the mandrel 14 and an end secured to end plate 20 by means of bolts 25a. Outer casing 11 may then be slipped over the rubber sleeve until it abuts end plate 20 and it may then be secured in position by cap 22. End plate 21 with tapering members 29 and 30 may then be slipped over the end of mandrel 14 with bolts 25a passing through the end plate so that their threaded ends may be secured with nuts in the usual manner. The assembly may then be completed by attaching cap 23 to outer case 11.

The device of the present invention is particularly adapted for attachment to a pipe or line carrying a stream of liquid having a pulsating pressure for the purpose of suppressing or dampening the vibration in the liquid. For use in such service it is desirable to secure a supply of compressed air to valve 19 and fill the chamber 18 with air at a pressure approximating the minimum pressure encountered in the pulsating stream. The device may then be fluidly connected by any conventional means, as by screw threads 16, to the pulsating stream. It will be understood that when compressed fluid is placed in cavity 18 without a corresponding pressure within mandrel 14, the inner surface of sleeve 17 is forced against the outer surface of mandrel 14. Upon connecting the device with the source of pulsating pressure, the rubber sleeve will move through a cycle. Because of the compressible fluid maintained within cavity 18, the outer surface of sleeve 17 cannot be forced into direct physical contact with the inner surface of case 11. The inner surface of rubber sleeve 17 may or may not come into physical contact with the outer surface of mandrel 14 during that period in each cycle wherein the fluid pressure is a minimum within mandrel 14. It is preferred to adjust the pressures in cavity 18 and the pressure within the mandrel 14 during the cycle of pulsation so that the surfaces of rubber sleeve 17 do not come into physical contact with the surface of mandrel 14. In other words, it is desirable for rubber

sleeve 17 to be forced outwardly away from mandrel 14 during the high pressure portion of the cycle and toward the mandrel during the low pressure part of the cycle without coming into direct contact with the mandrel; the reason for not wishing to have direct contact between the rubber sleeve and the mandrel is to reduce the wear on the rubber sleeve. It will be understood that under some conditions of service it may be necessary or desirable for the inner surface rubber sleeve 17 to come in contact with mandrel 14 during a portion of each cycle.

It will be understood that the device of the present invention may be constructed of material of suitable structural strength and dimensions adapted to the service intended. As a specific example, given by way of illustration and not intended to limit the invention in any way, it may be stated that suitable dimensions for a pulsation dampener adapted to dampen the pulsations in drilling fluid being passed from the outlet port of one pump to the inlet port of another pump when compounding mud pumps in a rotary drilling rig may have an outer casing 11 with an outside diameter 12 $\frac{1}{4}$ inches, a wall thickness of $\frac{3}{4}$ inch and a length of 45 inches. The rubber sleeve 17 may have a normal outside diameter of 7 inches and a thickness of $1\frac{1}{2}$ inches while the mandrel 14 may have an outside diameter of approximately 4 inches.

While I have described the specific embodiment of the present invention it will be understood by a workman skilled in the art that various changes in the shape, size and proportion of the device may be made without departing from the scope of the invention.

Having fully described and illustrated the device of the present invention, what I desire to describe as new and useful and to secure by Letters Patent is:

1. In a pulsation dampener including a tubular mandrel having its central portion perforated, a flexible deformable sleeve having a wall arranged concentrically outside said mandrel, and a tubular casing arranged concentrically outside said sleeve, the improvement which comprises wedge-shaped end portions on each end of the wall of said sleeve with each wedge-shaped portion diminishing in thickness toward the distal end, a pair of annular end plates adapted to be arranged in said dampener at first and second ends, and spaced apart first and second wedge-shaped annular seating members abutting against said end plates enclosing a recess adapted to receive the wedge-shaped ends of said sleeve.

2. In a pulsation dampener including a tubular mandrel having its central portion perforated, a flexible deformable sleeve having a wall arranged concentrically outside said mandrel, and a tubular casing arranged concentrically outside said sleeve, the improvement which comprises wedge-shaped end portions on each end of the wall of said sleeve with each wedge-shaped portion diminishing in thickness toward the distal end, a pair of annular end plates adapted to be arranged in said dampener at first and second ends, spaced apart first and second wedge-shaped annular seating members abutting against said end plates enclosing a recess adapted to receive the wedge-shaped ends of said sleeve, and means to draw said wedge-shaped ends into said recesses.

3. In a pulsation dampener including a tubular mandrel having its central portion perfo-

rated, a flexible deformable sleeve having a wall arranged concentrically outside said mandrel, and a tubular casing arranged concentrically outside said sleeve, the improvement which comprises wedge-shaped end portions on each end of the wall of said sleeve with each wedge-shaped portion diminishing in thickness toward the distal end, a pair of annular end plates adapted to be arranged in said dampener at first and second ends, spaced apart first and second wedge-shaped annular seating members abutting against said end plates enclosing a recess adapted to receive the wedge-shaped ends of said sleeve, an annular supporting member embedded in the wedge-shaped ends of said sleeve, and 15

means attached to said annular supporting member for drawing the ends of said sleeve into said recesses.

DOUGLAS RAGLAND.
